UNITED STATES PATENT OFFICE

A. VINTON STEGEMAN, JR., OF FORT THOMAS, KENTUCKY, ASSIGNOR TO THE WADSWORTH WATCH CASE COMPANY, OF DAYTON, KENTUCKY, A CORPORATION OF KENTUCKY

DESIGN FOR A COMBINED WATCHCASE AND BRACELET

Application filed August 16, 1930. Serial No. 36,683. Term of patent 14 years.

To all whom it may concern:

Be it known that I, ALBERT VINTON STEGEMAN, Jr., a citizen of the United States, residing at Fort Thomas, in the county of Campbell and State of Kentucky, have invented a new, original, and ornamental Design for a Combined Watchcase and Bracelet, of which the following is a specification, reference being had to the accompanying drawings, forming part thereof:

Fig. 1 is a plan view of a watch case and part of a bracelet;

Fig. 2 is an edge view of the disclosure in Fig. 1;

Fig. 3 is a perspective view of the watch case;

Fig. 4 is a perspective view of a portion of the bracelet;

Fig. 5 is a section on the line 5—5 of Fig. 1;

Fig. 6 is a section on the line 6—6 of Fig. 1; and

Fig. 7 is a perspective view on a reduced scale of a combined watch case and bracelet showing the essential features of my new design in full lines.

I claim:

The ornamental design for a combined watch case and bracelet, substantially as shown and described.

A. VINTON STEGEMAN, JR.
